UNITED STATES PATENT OFFICE.

HARRY WILLIAM MOBBS AND ALFRED LEWIS, OF KETTERING, ENGLAND.

TREE FOR BOOTS OR SHOES.

SPECIFICATION forming part of Letters Patent No. 589,666, dated September 7, 1897.

Application filed January 23, 1897. Serial No. 620,877. (No model.)

To all whom it may concern:

Be it known that we, HARRY WILLIAM MOBBS and ALFRED LEWIS, boot-last manufacturers, residing at Kettering, in the county 5 of Northampton, England, have invented certain new and useful Improvements in Trees for Boots or Shoes, of which the following is a specification.

The present invention has reference to trees 10 for boots and shoes, and relates more particularly to those that are used in factories in the treeing, shaping, and polishing operations just before the boots are sent out ready for sale.

As an operator has many pairs of boots or 15 shoes through his hands in a single day, each of which he has to put upon the trees and remove therefrom after treatment, it is of great importance that he should be able to put the boots on and off of the trees easily and quickly 20 without straining the boot.

With the ordinary tree having the usual rigid fore part there is considerable resistance during insertion and removal by reason 25 of the point of the toe bearing heavily upon the bottom or insole of the boot being treed. In overcoming this resistance much skill and and more or less force has to be employed, which sometimes rucks up the sock and strains 30 the boot.

The object of our invention is to construct 35 the feet of the trees so as to facilitate the application and removal of the boots and shoes, thereby increasing the daily output in the hands of a single operator, who when aided by our invention need not have acquired that knack which the best and quickest operators now appear to possess and without which the application and removal of the boot is exceedingly difficult.

In carrying out our invention we joint the 40 tree at the toe, so as to permit it to turn upward like the toes of the human foot when the boot is being applied or removed, such turning or bending upward greatly facilitating the application and removal of the boot, so that it can be readily accomplished by any 45 ordinary unskilled hand.

Our invention consists in the novel con-

struction of the toe-joint, as hereinafter described and claimed.

In the accompanying drawings, Figure 1 shows in side view a tree-foot embodying our present invention. Figs. 2 and 3 are detached plan and end views of a preferred form of joint in an open position, and Fig. 4 is an end view 55 of the same joint closed.

It will be seen that the toe part *a* of the tree is jointed to the after part *b* in such a way that it can be bent upward into the drawn position.

The normal position of the parts is that shown by the dotted lines, and the bent position is that assumed during the insertion of the tree into the boot or its removal therefrom. If desired, a spring or springs *x* may 65 be provided, as shown in the drawings, to impart a tendency to the toe part to resume, after bending, the normal or dotted position.

The joint which we have selected for illustration comprises a pair of metal plates, pref- 70 erably malleable cast-iron.

c is one plate screwed to the toe part *a* of the tree and carrying curved arms or projections *c' c'*. *d* is the other plate, screwed to the part *b* of the tree, having holes to receive the 75 arms *c'*.

Before fixing the plates in position in the tree they are fitted together by passing the arms *c'* through the holes in the plate *d* and securing them by pins *e*, passed transversely 80 through the ends of the said arms. When fixed in position, the connected plates *c d* shackle together the parts *a b* of the tree and form a joint which permits the parts to lie closely together, as seen in the dotted position 85 of Fig. 1, (the arms *c'* in that case projecting into a space prepared in the tree at the back of the plate *d*,) or allows the parts *a b* to be drawn asunder and bent into the position shown in full lines in the same figure. A dis- 90 tinguishing characteristic of this joint is that all parts of the connection between the toe part *a* and the principal part *b* of the tree-foot are entirely within the tree, not any of said parts being at the surface of the tree. This, besides 95 enabling a perfectly close joint to be made be-

tween the two parts *a* and *b* when the part *a* is in its normal position, permits the wooden parts of the tree to be rasped or cut to change the shape of the tree after the parts have been 5 permanently connected.

What we claim as our invention is—

In toe-jointed trees for boots and shoes, the hinge or shackling device above described,

consisting of plates secured to the divided portions of the tree, and connected together by 10 curved arms, substantially as set forth.

HARRY WILLIAM MOBBS.

ALFRED LEWIS.
